UNITED STATES PATENT OFFICE.

KARL A. NORRMAN, OF LYNN, MASSACHUSETTS, ASSIGNOR TO GENERAL ELECTRIC COMPANY, A CORPORATION OF NEW YORK.

MEANS FOR REVERSING TWO-CYCLE ENGINES.

1,148,042.

Specification of Letters Patent.

Patented July 27, 1915.

Application filed November 12, 1913. Serial No. 800,518.

To all whom it may concern:

Be it known that I, KARL A. NORRMAN, a subject of the King of Sweden, residing at Lynn, county of Essex, State of Massachusetts, have invented certain new and useful Improvements in Means for Reversing Two-Cycle Engines, of which the following is a specification.

The present invention relates to means for reversing two-cycle internal combustion engines in which the scavenging pump is utilized for such purpose as an air motor and has for its object to improve and simplify the construction of the controlling mechanism.

In the accompanying drawings which illustrate one of the embodiments of my invention, Figure 1 is an axial section of a part of an internal combustion engine operating on the high compression cycle; Fig. 2 is a cross-section of the same through the valves controlling the scavenging pump; Fig. 3 is a detailed view showing a modification of the means for admitting scavenging air to the working cylinder, and Fig. 4 is a detail view showing the shapes of the cams that actuate the discharge.

5 illustrates the working cylinder which may be of any suitable construction. It is provided with a removable head 6 having a water jacket 7. The cylinder may also be provided with a similar water jacket. In the head is located a fuel injector 8 of any suitable construction and the passage of fuel and injection air into the engine is controlled by the needle valve 9. The operating mechanism for the needle valve has been omitted in the interest of simplicity of illustration, but it is to be understood that any suitable form of such mechanism may be employed. Fuel from a suitable source of pressure such as a pump is admitted to the injector by the pipe 10, and the so-called injection or blast air is admitted by the pipe 11. Located in the cylinder is a piston 12 which is provided with a head 13. On opposite sides of the head and extending in the direction of the length of the cylinder are ribs or partitions 14 which serve to direct the scavenging air over the top of the piston as it flows from the scav-

enging ports to the exhaust ports. The piston is connected to the main shaft 15 by a connecting rod 16 in any ordinary or suitable manner. The cylinder is provided on one side of the center with exhaust ports 17, Fig. 2, which discharge into a chamber 18, the latter communicating with the conduit 20 leading directly or indirectly to the atmosphere. The cylinder is also provided with scavenging ports 21 on the other side of the center which communicate with a chamber 22, the latter receiving air from the receiver 23. Interposed between the receiver and the chamber 22 is a shut-off valve 24 of any suitable construction. The piston 13 is arranged to control both the scavenging and the exhaust ports. In the normal operation of the engine the piston uncovers the exhaust ports at the end of the firing stroke and shortly thereafter air is admitted through the ports 21 on the other side from the chamber 22. Owing to the use of the ribs 14 on the piston head the air from the ports 21 is caused to flow longitudinally along the cylinder wall in one direction, thence over the top of the piston down the cylinder wall on the other side. In other words, the ribs 14 prevent the scavenging air from flowing directly across the top of the piston from one side of the cylinder to the other. This arrangement insures good scavenging which is essential for successful operation. After the cylinder is properly scavenged the piston starts its compression stroke and compresses the air in the cylinder to a temperature above the igniting temperature of the fuel. At or about the inner dead center of the piston the fuel valve 9 is opened and fuel is injected into the cylinder by the so-called blast air.

Situated at one side of the working cylinder is a scavenging pump or air compressor 25. This scavenging pump or compressor may be formed as a part of the same structure as the working cylinder or it may be a separate structure and supported in any suitable way. It comprises a suitable cylinder and a reciprocating piston 26, the latter having a rod 27 which is connected to the main shaft of the engine in any usual or well known manner, for example by a con-

necting rod 27^a and cross-head. As shown the pump is of the double acting type, and is provided with suction or inlet valves 28 at each end and also with discharge valves 29. Since these valves are similar in construction a description of one set, or pair, will be sufficient. The valves as shown are of the puppet type, although my invention is not necessarily limited thereto. The valves are operated by bell crank levers 30 and 30^a, each acting through a collar or abutment 31 on the valve spindle. The bell crank levers 30 and 30^a are offset sufficiently to engage the various cams illustrated in Fig. 1. The positive operation of the valves is essential to reduce throttling losses, especially for fast running engines, and should not be regarded as a complication introduced for starting and reversing purposes only. Each valve is provided with a coiled compression spring 32 tending to hold it on its seat. The suction valve 28 is arranged to open inwardly and the discharge valve to open outwardly. The bell crank levers are mounted on suitable brackets 33 and are provided with antifriction rollers 34 that engage the cams on the shaft 35, the latter being rotated by any suitable driving connection from the main shaft. On the shaft 35 there are for each pair of pump valves four cams, of which 36 is for the suction valve and 37 for the discharge valve. These suffice for operating the pump and engine in one direction only. The cams for the discharge valves are so shaped as to open said valves only after a certain compression has been attained, say four or five pounds gage for example. The suction valve cams on the other hand are so shaped as to open said valves during the whole stroke of the pump piston. For reverse operation a second set of similar cams 38 and 39 are provided but angularly displaced from cams 36-37 by substantially 180 degrees. Of these 38 is for the suction valve and 39 for the discharge valve. Each pair of cams is connected by a smooth neck 40 so no difficulty will be experienced in shifting from one operating condition to another. As shown the discharge valve cams 37-39 are located between the suction valve cams. To provide for this the bell crank levers for the former cams are offset from those of the latter as indicated in dotted lines in Fig. 1. It is also to be noted that the cams on the one end of the shaft are angularly displaced by 180 degrees from those on the other end, this being necessary to admit air to the cylinder on one side of the piston when the latter is compressing air on the other side. Air is admitted to the suction valve casing from the chamber 41, Fig. 2, which is connected to the atmosphere. After the compressed air passes the discharge valves 29, it enters the chamber 42 from which it flows to

and is stored in the receiver 23. The cam shaft 35 is supported in suitable bearing brackets 43 and is capable of being moved in an axial direction by the hand lever 44, the latter being pivoted at 45 and provided with a spring pressed latch 46, one end of which is adapted to enter openings 47 in a quadrant or sector 48 and lock the lever in either of its two positions. In order to permit the cam shaft 35 to slide, one of its ends enters a square socket in a member 49, the latter being carried by a shaft 50 driven by the main shaft 15 through suitable gearing.

To the receiver 23 is connected a tank 51 commonly known as a starting bottle and containing highly compressed air. In the pipe connecting the bottle with the receiver is a shut-off valve 52.

In Fig. 3 is shown in section an engine in which the admission of scavenging air to the working cylinder is controlled by the valve 53 instead of by the working piston as in Fig. 1. This valve may be operated in the usual manner.

For simplicity I have shown my invention applied to an engine having only a single working cylinder, but it is evident that as many of such cylinders may be provided as are desired.

In Fig. 4 is shown a detail view of one of the discharge valves 29 and also the cam 37 for actuating it. The cam 39 for running in the reverse direction is indicated in broken and dotted lines.

The operation of the starting mechanism is as follows: When the engine stops some one of the discharge valves 29 will be open, that is to say is in position to let air from the pump pass into the receiver, the suction valve on the corresponding end; i. e. the one in alignment therewith, being closed. The valve 24 is first closed to shut off the receiver from the scavenging chamber 22 and its ports 21. The valve 52 is then opened and highly compressed air from the tank or bottle 51 flows into the receiver, thence through the valve chamber 42 and past the valve 29 into the pump cylinder where it acts on the piston 26 to start it into operation and thus turn the main shaft 15 and move the working piston 13. It is to be noted that the valve 29 which was the discharge valve for normal operation has under conditions of starting become the inlet or admission valve. The setting of the cams as heretofore described will under these conditions start the engine backward. Should the engine have stopped before the discharge valve 29 had a chance to open it will be necessary to bar the engine over to a suitable starting position. As these valves remain closed for only about one-eighth to one-sixteenth of the stroke this is not of special importance. In a multi-cylinder engine with two pumps set 90 degrees apart

some discharge valve will be open at least enough to turn the engine to starting position when another valve 29 will freely admit starting air to the pump cylinder.

5. To start the engine in the normal running direction, it will be necessary to move the cam shaft toward the main shaft, so that the second set of cams will be put into service. In normal running the discharge valve 29 opens only after a part of the stroke of the pump piston is completed. In starting, said valve closes after the greater part of the stroke is completed, and which results in a certain degree of expansion of the starting air in the pump cylinder. When the pump crank passes its dead center the suction valve 28 opens and air in the pump cylinder escapes to atmosphere. Under these conditions the suction valve serves 15 as an exhaust valve. As this valve remains open during the whole stroke stalling of the engine due to compression in the pump cylinder cannot occur.

As soon as the mixture in the working cylinder is fired the engine operates under its own power and the valve 52 at the tank is closed and the valve 24 between the receiver and scavenging chamber is opened. Should it be desired to bring the engine up 25 to speed or cause it to drive a load before the starting air is shut off, the valve 24 can be partly opened so as to allow, by sufficient throttling, the use of the starting air for scavenging purposes.

35 For reversing, the operations are exactly the same except that lever 44 is left in the normal running position; *i. e.*, that shown, when the starting air is admitted.

In accordance with the provisions of the 40 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. In combination, an internal combustion engine, a scavenging pump driven thereby, a receiver that receives air from the pump and delivers it to the engine during normal operation, valve means controlling the action of the pump, and a source of fluid 50 under pressure that supplies fluid to the receiver from which it passes to the pump cylinder for the purpose of starting the engine.

2. In combination, an internal combustion engine, a scavenging pump driven thereby, a receiver that receives air from the pump and delivers it to the engine during normal operation, valve means controlling the action of the pump, sets of cams for actuating the valves, means for moving one 55 set of cams or the other into position to

actuate the valves, and a means supplying compressed air to the receiver from which it passes through the normal discharge valve of the pump into the pump cylinder for starting the engine.

3. In combination, an internal combustion engine, a scavenging pump driven thereby, suction and discharge valves for the pump, cams for positively actuating them, a receiver that receives compressed air from the pump subject to the control of the discharge valve and delivers it to the engine during its normal operation, a source of high pressure fluid adapted to supply fluid to the receiver from which it passes through the normal discharge valve of the pump into its cylinder for starting its piston and that of the engine into operation, the suction valve of said pump in the meantime acting as an exhaust valve, and means for controlling the passage of fluid from the receiver to the engine cylinder for scavenging it.

4. In combination, an internal combustion engine, a scavenging pump driven thereby, suction and discharge valves for the pumps, a pair of cams for positively actuating each of said valves, one of said cams being angularly displaced with respect to the other, a means for moving one or the other of said cams into operative relation to its valve, a receiver that receives air from the pump and delivers it to the engine for scavenging purposes, a valve between the receiver and the engine, and a controllable source of fluid pressure which is connected to the receiver for admitting fluid thereto from which it passes into the pump and acts on its piston to start the engine subject to the control of said valves.

5. In combination, an internal combustion engine, a double acting scavenging pump driven thereby, a receiver that receives air from the pump and delivers it to the engine cylinder during normal operation, positively actuated valve means controlling the admission of air to each end of the pump cylinder and the discharge therefrom, a means for supplying high pressure fluid to the receiver from which it passes through said valve means to the pump cylinder for starting purposes, and a valve interposed between the receiver and the engine cylinder by means of which the passage of air to the latter can be controlled.

6. In combination, an internal combustion engine, a scavenging pump driven thereby, positively actuated suction and discharge valves for the pump, the suction valve being opened during the entire suction stroke and the discharge valve being opened only during the later part of the discharge stroke, a receiver that receives air from the pump and delivers it to the engine during normal operation, and a source of fluid under pres-

1,148,042

22

sure that supplies fluid to the receiver from which it passes to the pump cylinder by way of the discharge valve for starting the engine, said suction valve at such times acting as the exhaust, and means for disconnecting the receiver from the engine.

In witness whereof, I have hereunto set

my hand this seventh day of November, 1913.

KARL A. NORRMAN.
